UNITED STATES PATENT OFFICE.

BARTON P. JENKS, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

DESIGN FOR A HANDLE FOR SPOONS, FORKS, OR SIMILAR ARTICLES.

51,381.

Specification for Design.

Patented Oct. 16, 1917.

Application filed September 6, 1917. Serial No. 190,091. Term of patent 14 years.

To all whom it may concern:

Be it known that I, BARTON P. JENKS, a citizen of the United States, residing at Providence, in the county of Providence and State of Rhode Island, have invented a new, original, and ornamental Design for Handles for Spoons, Forks, or Similar Articles, of which the following is a specification, reference being had to the accompanying drawings, forming part thereof.

Figure 1 is a view of the obverse side of the spoon, showing my design.

Fig. 2 is a view of a portion of the reverse side of the spoon, showing my design.

Fig. 3 is a cross sectional view of the handle of the spoon, on the line 3—3 of Fig. 1.

I claim—

The ornamental design for a handle for spoons, forks or similar articles, as shown.

BARTON P. JENKS.
